BUILDING BLOCKS

Filed May 4, 1931

Attorney

UNITED STATES PATENT OFFICE

JOHN H. DOAK, OF SEASIDE, OREGON

BUILDING BLOCKS

Application filed May 4, 1931. Serial No. 534,918.

My invention is intended for building blocks and as educational blocks and as toys. Heretofore building blocks and toy blocks

5 have been made of wood, metal, or other rigid material and through the use of such material children hurt themselves and damage floors, table and other structures upon which the same are to be used.

In the use of building blocks now in common use, the same are left upon floors and when so left children and adults are subject to damage through falling, upon, or stumbling over the same.

10 In the building blocks heretofore used there was no way by which structures could be built by the application of the block members to walls, or other vertical members, or supported from ceilings.

15 Through the use of my new and improved blocks the same may be secured by the vacuum cup, to any supporting structure and be built outward or downward therefrom.

20 My new and improved block is comprised of a hollow cubical member having a plurality of cylindrical recesses disposed upon some of the faces of the blocks and vacuum cups disposed in certain other faces of the blocks.

25 Cylindrical members are adapted for being placed within certain of the recesses of adjacent faces so that structures may be created by the securing of the blocks together.

30 Live rubber is used to afford greatest resiliency to the blocks and to permit of maximum utility.

35 One of the objects of my invention is to provide a building block that may be used by children and through the use of which the child, or user may not be hurt.

40 A still further object of my invention consists in providing a building block that is light in weight, that may be expanded into various structures and that may be used as educational, as well as building blocks.

45 With these and incidental objects in view, the invention consists in certain novel features of construction and combination of parts, the essential elements of which are set forth in the appended claims, and a preferred form of embodiment of which is hereinafter

shown with reference to the drawing which accompany and form a part of this specification.

In the drawing:

Fig. 1 is a front view of a structure that 55 may be made from my new and improved blocks. The structure illustrated in Fig. 1 is supported upon a horizontal support.

Fig. 2 is a side view of a structure built 60 from my new and improved blocks illustrated as being secured to and supported upon a vertical surface.

Fig. 3 is a perspective side view of one of my new and improved blocks.

Fig. 4 is a perspective end view of one of 65 the fastening cylinders adapted for securing adjacent blocks together.

Fig. 5 is a sectional side view of a pair of blocks illustrated as being secured together by the cylindrical member, illustrated in 70 Fig. 4.

Fig. 6 is a perspective end view of a half section of a cubical block.

Fig. 7 is a sectional end view of a half 75 section of a cubical block.

Fig. 8 is a perspective top side view of a pair of half section blocks as illustrated in Figs. 6 and 7 secured together by a common fastener of the type illustrated in Fig. 4.

Like reference characters refer to like parts 80 throughout the several views.

My building unit 1 is preferably made of live rubber. A void 2 comprises the major portion of the block unit. Relatively thin walls 3 produce a light, inexpensive block 85 and gives the block its greatest utility. Recesses 4, preferably made cylindrical are disposed in the oppositely disposed faces of some of the sides of the blocks. A cylinder 5 is adapted for being placed within the recesses 4. The cylinder 5 being substantially twice the length of the depth of the recesses 4, in order that the cylinder may be used in the fastening of the blocks together. When so made the meeting faces 6 and 7 of the blocks, when secured together, by the cylinder, will closely engage each other. The diameter of the cylinder 5 should be made slightly larger than the diameter of the recess 4 in order that a gripping connection 90

95

100

may be created between the cylinder 5 and the recess 4.

Recesses 8 are formed in other faces of the blocks which may form a vacuum cup when 5 the blocks are fixedly and forcibly engaged against each other, or against a supporting wall, or other surface, or ceiling.

I have illustrated in Fig. 2, a plurality of blocks 9 and 10 as being secured to a vertical 10 wall 11 and a structure built outward from the wall through the use of the vacuum cup connection.

Indicia 12 may be formed within the vacuum cup faces, or within the recesses 4 15 and indicia 13 may be placed within all, or some of the ends of the cylinder 5. Instead of using indicia upon, or within some of the recesses, animals, or other configuration may be formed therein.

20 In order to give greater construction possibilities to my new and improved block, I may desire to make some of the blocks as illustrated in Figs. 6, 7 and 8, and when so made the blocks are made in half section of 25 the cube with a diagonal cut 14 being made through the block at its longest diameter to form two half section blocks 15 and 16. The cylindrical recess being formed within the long face 17 of the block. This greatly increases the construction possibilities of the 30 assembly without departing from the spirit of the invention.

While the form of mechanism herein shown and described is admirably adapted to fulfill 35 the objects primarily stated, it is to be understood that it is not intended to confine the invention to the one form of embodiment herein shown and described, as it is susceptible of embodiment in various forms, all coming 40 within the scope of the claims which follow.

What I claim is:

1. In educational and amusement devices of the class described formed of a plurality of blocks, a resilient block having recesses 45 formed within some of the faces of the block, said recesses being in corresponding positions in each block, a compressible engaging element whose uncompressed diameter is slightly greater than the diameter of the recesses 50 adapted to be disposed within the recesses of other blocks, and a recess disposed in one of the remaining faces of the block adapted to maintain the block fixedly disposed relative to a supporting surface.

55 2. In educational and amusement blocks of the class described comprising a plurality of cubical blocks, a resilient block having cylindrical recesses disposed within some of its faces, a cylinder adapted to intimately 60 engage within the recesses of the similar blocks, and a recess disposed within one of the faces of the block adapted to maintain it in a fixed position relative to a supporting surface.

65 3. In educational and amusement devices

of the class described, comprising a plurality of polyhedral blocks, a resilient block having cylindrical recesses disposed within some of its faces, a recess disposed within one of the faces of each one of the blocks, 70 said recess adapted to hold the block fixed relative to a supporting surface, and means formed integral with the block for detachably attaching the block to a similar block, said means adapted to intimately engage 75 within the recesses.

4. In educational and amusement devices of the class described, comprising a plurality of resilient polyhedral blocks, a resilient block having a plurality of cylindrical recesses disposed within its faces, and a plurality of resilient cylinders adapted to intimately engage within the recesses of a like block, said recesses also adapted to aid in the detachably attaching of the block to a 85 supporting surface.

5. In educational and amusement devices of the class described, a block of resilient material to be used in a set of similar blocks, circular recesses disposed within some of the 90 faces of the block, circular projecting lugs, of greater diameter than the recesses, disposed upon other of the faces of the block, and adapted to engage within the recesses of other blocks of the set, any recess when 95 not occupied by a lug adapted to act as a vacuum cup in maintaining the block upon a surface other than horizontal.

JOHN H. DOAK.
